United States Patent Office

Des. 225,008
Patented Oct. 31, 1972

225,008

FISHING LURE

Carl R. Cordell, Jr., 215 Idlewood Drive,
Hot Springs, Ark. 71901

Filed Dec. 4, 1970, Ser. No. 26,298

Term of patent 14 years

The portion of the term of the patent subsequent to
Feb. 20, 1982, has been disclaimed

Int. Cl. D22—05

U.S. Cl. D22—27

FIG. 1.

FIG. 3.

FIG. 2.

FIG. 4.

FIG. 5.

FIG. 6.

FIG. 8.

FIG. 7.

FIG. 9.

FIG. 10.

FIG. 1 is a top plan view of a fishing lure showing one form of my design;

FIG. 2 is a side elevation thereof;

FIG. 3 is a front elevation thereof;

FIG. 4 is a rear elevation thereof;

FIG. 5 is a bottom plan view thereof;

FIG. 6 is a top plan view of a fishing lure showing another form of my design;

FIG. 7 is a side elevation thereof;

FIG. 8 is a front elevation thereof;

FIG. 9 is a rear elevation thereof; and

FIG. 10 is a bottom plan view thereof.

The broken line conventional hook members are shown in FIG. 2 for illustrative purposes only.

I claim:

The ornamental design for a fishing lure, as shown and described.
